CLAIM

The ornamental design for a portable scenes light, as shown and described.

DESCRIPTION

FIG. 1 is a perspective view of a portable scenes light showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines immediately adjacent the shaded areas represent the bounds of the claimed design, while all other broken lines are directed to portions of the portable scenes

(Continued)

light and are for illustrative purposes only; the broken lines form no part of the claimed design.
